UNITED STATES PATENT OFFICE.

HENRY G. REIST, OF SCHENECTADY, NEW YORK, ASSIGNOR TO THE GENERAL ELECTRIC COMPANY, OF NEW YORK.

DESIGN FOR AN ARMATURE-SPIDER.

SPECIFICATION forming part of Design No. 25,528, dated May 19, 1896.

Application filed February 19, 1896. Serial No. 577,619. Term of patent 14 years.

To all whom it may concern:

Be it known that I, HENRY G. REIST, a citizen of the United States, residing at Schenectady, county of Schenectady, State of New York, have invented and produced a new and original Design for Armature-Spiders for Dynamo-Electric Machines, (Case No. 359,) of which the following is a specification, reference being had therein to the accompanying drawing, which is a view in perspective of an armature-spider constructed according to my design.

The leading feature of my design is a number of similar arms of the particular configuration shown and connected at the center of the spider, but not connected at its outer rim.

Referring now by letter, A is an opening in the center of the spider. B is a central boss or hub. G are keyways or slots, and C are the different arms to which I have referred.

Each arm C comprises a central portion and an expanded head or face part D, having lugs or enlargements E substantially equidistant from the center of the arm. In the face of each lug is a tenon or dovetail F.

I have illustrated my design as embodied in a six-arm spider; but I consider spiders of other numbers of arms of the particular configuration set forth to be included in my invention.

Having thus described my invention, what I claim is—

The design for the armature-spider, substantially as described and shown.

In witness whereof I have hereunto set my hand this 28th day of January, 1896.

HENRY G. REIST.

Witnesses:

B. B. HULL,

GENAVIEVE HAYNES.
